PACKING SHEET

Dermot Best, Dollingstown, Northern Ireland, assignor to Lurgan Boxmaking Company, Ltd., Lurgan, Northern
Ireland, a corporation of Great Britain

Application November 23, 1953, Serial No. 27,705

Term of patent 14 years

(Cl. D58—13)

Fig. 1

To all whom it may concern:

Be it known that I, Dermot Best, a citizen of Great Britain, residing at Dollingstown, county of Down, Northern Ireland, have invented a new, original, and ornamental Design for a Packing Sheet, of which the following is a specification, reference being had to the accompanying drawing, forming part thereof.

Fig. 1 is a plan view of the packing sheet of the new design shown in unfolded condition;

Fig. 2 is a front elevation of the packing sheet as shown in Fig. 1, in unfolded condition; and

Fig. 3 is a perspective view of the packing sheet of Fig. 1 shown in folded condition.

What is claimed:

The ornamental design for a packing sheet, as shown.
